UNITED STATES PATENT OFFICE.

NATHAN HATCH, OF ALBANY, NEW YORK.

UNDERGARMENT.

SPECIFICATION forming part of Letters Patent No. 594,794, dated November 30, 1897.

Application filed November 4, 1896. Serial No. 611,008. (No model.)

To all whom it may concern:

Be it known that I, NATHAN HATCH, of Albany, in the county of Albany and State of New York, have invented new and useful 5 Improvements in Undergarments, of which the following is a specification.

My invention relates to improvements in that class of garments known as "underwear," but especially to undershirts and union 10 garments in which an undershirt and drawers are comprised in one garment; and the object of my invention is to afford facilities for drawing on the garment either over the head or the feet of the wearer, as may be 15 preferred.

It is a well-known fact that considerable difficulty is experienced in drawing on an undershirt over the head by reason of the small size of the neck-opening, and this difficulty exists more particularly in knit goods, wherein from their elastic quality provision is always made to allow the goods to stretch to fit closely to the form of the wearer, the neck-opening in that class of goods being usually 20 too small to allow the head of the wearer to pass comfortably through said opening without disheveling the hair. It is also a well-known fact that when such garments are for children of tender growth, who generally depend upon a parent or attendant to change 25 their clothing, their little arms are frequently strained and sometimes injured by extending them over their heads to have the sleeves drawn into place thereon. By affording facilities for drawing on the undergarment over 30 the feet this danger is entirely avoided. In my improvement the transverse opening at the upper end of the body of the garment is of substantially the same width as the largest 35 part of the body of the garment, and at the upper end of the back of the latter there is a bifurcated flap which forms two tabs that may be either integral therewith or attached thereto, which when folded down upon the 40 front of the garment will join together at their straight edges and virtually form a chest-protector. Each of said tabs is provided with a semicircular indentation at or near its point of junction with the back of the garment, so 45 that when the two tabs are folded down upon the front of the garment said indentations will form a proper neck-opening that will

register with the transverse opening at the upper end of the tubular body of the garment and encircle the neck of the wearer.

55

In the accompanying drawings, which are herein referred to and form part of this specification, Figure 1 is a front elevation of a man's undershirt embodying my improvements, showing the tabs extended and separated in the manner they are before the garment is applied to the body of a wearer; and Fig. 2 is a like view of the garment with the tabs folded down and fastened together at their overlapping edges, the complementary 60 parts of a union garment being indicated by dotted lines.

It should be understood that my invention is equally adapted to male or female underwear, either adults' or children's, and whether 65 the garments are of knit goods or other textile fabrics.

As represented in the drawings, A designates the body of the garment, which is preferably made in a tubular form of a uniform 70 diameter; but it may be contracted in diameter at the waist-line, if preferred, and the openings at the upper and lower ends of the body are preferably made of like width, so that the garment may be drawn onto a wearer 75 by inserting the feet into the opening at the upper end of the body and pulling the garment upward into proper place. At the upper end of the back B two tabs C are formed or secured thereto, and semicircular indentations D are formed in said tabs near the upper 80 end of the back B, which, when the edges of said tabs are brought together, as shown in Fig. 2, will form a proper neck-opening E, that will fit the neck of a wearer. The tabs C 85 may be made in any preferred form; but preferably they are made of fabric similar to or exactly like the body of the garment, whether integral with or attached to said body, and they are shaped similarly to a-chest-protector, 90 so as to overlap at their adjacent edges, one of which is provided with buttons 1 and the other with buttonholes 2, by which the two 95 may be fastened together, but when preferred any other means for fastening the two parts together may be employed. The garment is provided with the usual form of sleeves F, which project laterally from both sides of the body A, at the upper end of the same, but for 100

summer wear the sleeves F may be omitted and armholes formed at opposite sides of the body corresponding to the places occupied by said sleeves.

5 It is obvious that, when preferred, this garment can be drawn on over the head in the usual manner of getting into undershirts. Then after it is in place on the body of the wearer and the arms properly inserted in the 10 sleeves of the garment the tabs C are turned over onto the breast of the wearer and the adjacent edges of said tabs fastened together by the means provided for that purpose.

In the union garment shown and indicated 15 in Fig. 2 the body of the garment is formed substantially as shown and described in respect to Fig. 1; drawer-legs G are formed on the lower end of the body, as indicated by dotted lines in Fig. 2. In this form of my invention it is necessary that the garment should 20 be drawn on over the feet of the wearer.

What I claim as my invention, and desire to secure by Letters Patent of the United States, is—

An undergarment comprising a body having at its upper part a transverse opening of practically the full width of the body, and a bifurcated flap at the upper end of the back containing a neck-opening that will register with the transverse opening of the body; the 25 separated limbs of said flap forming tabs which are adapted to fold over onto the front portion of the body and having sufficient width to allow the edges thereof to meet at the median line of the garment, substantially 30 as specified. 35

NATHAN HATCH.
